CLAIM

The ornamental design for a ebelskiver, as shown and described.

DESCRIPTION

FIG. 1 is a top perspective view of the ebelskiver;
 FIG. 2 is a bottom perspective view of the ebelskiver.
 FIG. 3 is a front view of the ebelskiver, the rear view being a mirror image thereof;

FIG. 4 is a top view of the ebelskiver;

FIG. 5 is a left side view of the ebelskiver, the right side view being a mirror image thereof; and,

FIG. 6 is a bottom view of the ebelskiver.
